US00D896484S

(12) **United States Design Patent** (10) **Patent No.:** **US D896,484 S**
(45) **Date of Patent:** **** Sep. 22, 2020**

(54) **SHOE SOLE**(71) Applicant: **Reebok International Limited**, London (GB)(72) Inventors: **Henry Hardigan**, Pawtucket, RI (US); **Matthew Montross**, Middleboro, MA (US); **Michael Andrews**, East Falmouth, MA (US)(73) Assignee: **Reebok International Limited**, London (GB)(**) Term: **15 Years**(21) Appl. No.: **29/659,621**(22) Filed: **Aug. 10, 2018****Related U.S. Application Data**

(60) Continuation of application No. 29/574,934, filed on Aug. 19, 2016, now Pat. No. Des. 827,265, which is a continuation of application No. 29/498,586, filed on Aug. 5, 2014, now Pat. No. Des. 764,782, which is a division of application No. 29/411,762, filed on Jan. 25, 2012, now Pat. No. Des. 713,134.

(51) **LOC (12) Cl.** **02-04**(52) **U.S. Cl.**USPC ..... **D2/947; D2/953**(58) **Field of Classification Search**USPC ..... **D2/902, 906, 908, 916, 918, 925, D2/946-962, 977; 36/313, 22 R, 24.5, 36/25 R, 28, 32 R, 34 R, 59 C, 67 A, 103**

Primary Examiner — T Chase Nelson*(74) Attorney, Agent, or Firm* — Sterne, Kessler, Goldstein & Fox P.L.L.C.(57) **CLAIM**

The ornamental design for a shoe sole, as shown and described.

DESCRIPTION

FIG. 1 is a perspective view of a shoe sole showing the claimed design;

FIG. 2 is a side view thereof; and,

FIG. 3 is a bottom plan view thereof.

The dashed broken lines in the figures show portions of the shoe sole and environment that form no part of the claimed design.

The dot-dashed broken lines in the figures show boundaries that form no part of the claimed design.

1 Claim, 3 Drawing Sheets# US D896,484 S
